(57) **CLAIM**

The ornamental design for a basket, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top perspective view of a basket, showing the first embodiment of the new design;

FIG. 2 is a front view of the basket shown in FIG. 1; rear view being identical;

FIG. 3 is a side view of the basket shown in FIG. 1; other side view being identical;

FIG. 4 is a top view of the basket shown in FIG. 1;

FIG. 5 is a bottom view of the basket shown in FIG. 1;

FIG. 6 is a top perspective view of a basket, showing the second embodiment of the new design;

FIG. 7 is a front view of the basket shown in FIG. 6; rear view being identical;

FIG. 8 is a side view of the basket shown in FIG. 6; other side view being identical;

FIG. 9 is a top view of the basket shown in FIG. 6; and,

FIG. 10 is a bottom view of the basket shown in FIG. 6.

The broken lines illustrate portions of the basket that form no part of the claimed design.
